United States Patent Office

Des. 202,200
Patented Sept. 7, 1965

202,200

GOLF-CLUB COVER OR SIMILAR ARTICLE

Jack R. Bates, 130 Roca Way, Monterey Park, Calif.

Filed June 2, 1964, Ser. No. 80,250

Term of patent 3½ years

(Cl. D34—5)

The essential features of my design reside in those portions shown in full lines.

I claim:

The ornamental design for a golf-club cover or similar article, substantially as shown and described.
